(57) **CLAIM**

The ornamental design for a garment, as shown and described.

DESCRIPTION

FIG. 1 is a rear left perspective view of a garment in accordance with an embodiment of the present design;

FIG. 2 is a rear elevation view thereof;

FIG. 3 is a front right perspective view thereof; and,

FIG. 4 is a front elevation view thereof.

The broken lines shown in the drawings depict portions of the garment that form no part of the claimed design.
